UNITED STATES PATENT OFFICE.

MARCUS PAGE EXLINE, OF DALLAS, TEXAS.

COVER FOR PASS-BOOKS.

1,054,522.

Specification of Letters Patent. Patented Feb. 25, 1913.

Application filed July 29, 1912. Serial No. 712,034.

To all whom it may concern:

Be it known that I, MARCUS PAGE EXLINE, a citizen of the United States, residing at Dallas, in the county of Dallas and State of 5 Texas, have invented certain new and useful Improvements in Covers for Pass-Books; and I do hereby declare the following to be a full, clear, and exact description of the invention, such as will enable others 10 skilled in the art to which it appertains to make and use the same.

This invention relates to improvements in pass books, and has as an object to provide a cover for such pass books having a 15 transparent portion through which printed matter contained in the book will be visible as the cover is closed.

A further object of the invention is to provide improved means of securing a transparent strip of material to the cover which will at once give the strongest construction and most pleasing appearance.

With these and other objects in view the invention comprises certain novel constructions, combinations and arrangement of parts as will be hereinafter more fully described and claimed.

In the drawings, where corresponding parts are represented by similar reference 30 characters; Figure 1 shows the upper portion of a book open with the invention applied to the cover. Fig. 2 is a section taken on line 2—2 through the cover shown in Fig. 1. Fig. 3 shows the plan of the celluloid blank before it is applied to the cover. Fig. 4 shows a somewhat modified form of the blank.

I am aware that heretofore pass books of the same general character described in this 40 application have been put upon the market, but I am also aware that there are certain objections inherent to the construction of such books which it is the object of this invention to correct.

45 One of the objections found with the present form of pass book is, that the celluloid, or other transparent flexible material, is not held in place very securely for the reason that it is very difficult for glue, mucilage or other securing fluids to grip the celluloid sufficiently to hold the same in place. The result of this is that the celluloid will work loose in time, due both to wearing and heat of the person carrying the 55 book, and thus cause annoyance. Another

objection due to the construction of these books is the appearance on the inside cover of a raised portion extending around the opening in the cover, which raised portion is due to the method of securing the celluloid in place. The present method of applying the celluloid is, to cut an opening in the cover of the pass book, then place the celluloid over the opening so that the edges of the celluloid will overlap those of the 60 cover opening and then secure the celluloid in place by fastening a cloth or paper to the inside of the book cover thus providing a means for holding the transparent material in place. Insomuch as this raised 65 portion terminates in edges which are usually sharp due to the character of the celluloid, the fastening paper or cloth will in time be cut so that the celluloid will work 70 loose. In order to overcome these objections 75 applicant provides an opening in the cover around which is formed a depression and into which depression the celluloid fits. This construction gives a pleasing appearance and also provides a structure which 80 will not cut the securing paper. As shown in the drawings, the cover of the book is provided with an opening 1 cut in any shape and so placed upon the cover as to be opposite printed matter upon the first leaf of 85 the book proper, so that as the cover is folded into place this printed matter will be directly under the opening 1. Upon the inside of the cover of the book and extending entirely around the opening 1 is a depression 2 of depth equal to the thickness 90 of the celluloid with which it is desired to cover the opening. It is to be understood that the showing in Fig. 2 is necessarily 95 exaggerated in order that the construction may be clearly shown.

Designed to properly fit the depression 2 is a sheet of celluloid 3, having a solid imperforate part which is designed to completely cover the opening 1. After the celluloid 3 has been placed into depression 2, a backing comprising a strip of securing paper or cloth 4 is pasted upon the inside of the cover to hold the member 3 in place, said cloth being provided with an opening which corresponds to the opening 1 in the cover. The celluloid member 3 has formed around the outer edges a series of comparatively large perforations 5, while extending within these perforations 5 is a series of much 100 105 110

smaller perforations 6 which are designed to fall just inside of the edges of opening 1 when the member 3 is placed in the depression 2. A suitable glue or mucilage is spread 5 over the bottom of depression 2 before the celluloid 3 is placed therein and a similar adhesive coating is spread over the lower side of the paper or cloth 4, so that as the whole is assembled there will be part of the 10 paper 4 which is held to the book cover by the glue insomuch as said glue can freely pass through the openings 5 and 6. It will be seen that insomuch as the perforations 6 are arranged very close to the edges of the 15 opening 1, by no ordinary accident will it be possible for the paper 4 or the cover of the book to become detached from the celluloid.

The modified form shown in Fig. 4 is similar to the form shown in Fig. 3 with the 20 single exception that the larger perforations 5 are replaced by serrations 7 formed on the outer edge of the blank 3. While these serrations permit the glue or other adhesive to secure the paper 4 to the cover of the book 25 yet it is found the construction shown in Fig. 3 gives a stronger construction than that shown in Fig. 4. The construction shown in Fig. 4 can be used where the depression 2 is not formed in the cover of the book for the 30 reason that the serrations 7 will form a gradual tapering which will be so slight as to be practically unnoticeable upon the inner side of the cover.

While only two forms of celluloid blanks 35 have been shown in this application it is to be understood that the design of the blank can be such as to meet any demands which will in the future be made upon pass book manufacturers, the important part of the 40 construction being the provision of several

sizes of perforations, the smallest of which lie just inside of the edges of the opening 1.

I claim:

1. A book cover provided with an opening, a transparent sheet having perforations 45 around the periphery thereof, a backing provided with an opening registering with the opening of the cover, part of the backing being secured to the cover, and an adhesive passing through the perforations and binding the remaining part of the backing to the 50 cover and transparent sheet.

2. A book cover provided with an opening, the cover being provided with a depression around the opening, a transparent sheet 55 located in the depression and having perforations in the periphery thereof, a retaining strip surrounding the depression, part of the strip being secured directly to the cover, and an adhesive passing through the 60 perforations and binding the remaining part of the strip to the cover and transparent strip.

3. A book cover provided with an opening, the cover being provided with a depression around the opening, a sheet of transparent material located in the depression having perforations near its edges and having rows of perforations parallel to and just inside of the edges of the opening, a backing 70 provided with an opening registering with the opening of the cover, and an adhesive passing through the perforations and binding the backing to the cover.

In testimony whereof I affix my signature 75 in presence of two witnesses.

MARCUS PAGE EXLINE.
